UNITED STATES PATENT OFFICE.

JOHN COSTELLO, OF ATTLEBOROUGH, MASSACHUSETTS, ASSIGNOR OF ONE-HALF TO JAMES F. SIMMS, OF SAME PLACE.

BUTTON.

SPECIFICATION forming part of Letters Patent No. 379,529, dated March 13, 1888.

Application filed July 29, 1887. Serial No. 245,585. (No model.)

To all whom it may concern:

Be it known that I, JOHN COSTELLO, of Attleborough, in the county of Bristol, State of Massachusetts, have invented certain new and useful Improvements in Hinged-Shoe Buttons, of which the following is a full, clear, and exact description, reference being had to the accompanying drawings, forming part of this specification.

10 This invention relates to a collar, cuff, or sleeve button having a hinged shoe, which may be tilted at an angle to the button-head, for entering the button in or removing it from a button-hole, and which may be placed parallel, or nearly so, with the button-head in order to lock and confine the button in a button-hole.

15 The objects of my invention are to improve this class of buttons and to render the hinging connection of the same stronger and more durable.

20 To the aforesaid purposes my invention consists in the certain novel and peculiar arrangement and construction of the several parts of the button, all as hereinafter fully described and claimed.

25 In the accompanying drawings, illustrating my invention, Figure 1 is a side view of my improved button with the lever-arms thrown down in substantially parallel relation with the button-head, and with the arms also shown in broken lines as drawn up in angular relation with the button-head; and Fig. 2 is a plan view of the same. Fig. 3 is a diminished detailed view of the several component parts of the button placed apart, though in their relative positions. Fig. 4 is an enlarged sectional view of Fig. 2, the section being taken on line 30 44 thereof. Fig. 5 is an enlarged sectional view of the top plate and the subjacent hinge-plate detached, the section being taken on line 45 55 in Fig. 2. Figs. 6 and 7 are sectional views of other forms of the improved parts of the device.

45 In the said drawings like numbers of reference designate corresponding parts throughout.

50 Referring to the drawings, the number 8 designates the cup-shaped cap-plate, in the concavity of which is seated the flat circular bottom plate, 9, which may, if desired, be made

of resilient material. The disk-like hinge-plate 10 is formed with an H-shaped central slot, 11, which is appropriate to receive the hinging T ends of the lever arms or posts 12 and 13, respectively, at the respective ends of the said slot. The hinge-plate 10 is placed intermediate the bottom plate, 9, and the top plate, 14, so that the hinging ends of the arms may be confined in their proper positions. The top plate, 14, is formed with the central opening, 15, through which the arms of the button may pass, and, if preferred, this plate may also be made of elastic material in order to give a better spring action to the movable parts of the button. The cap-plate 8 has its rim formed over upon the rim of the top plate, 14, so as to hold the three several plates together.

55 The lever-arms 12 and 13 are provided with the transverse bends 16 and 17 and 18 and 19, respectively, (shown clearly in Fig. 4,) and they are also provided with the hinging T ends 20 and 21, respectively, which take in the respective T-shaped ends of the slot 11 of the hinge-plate 10. The lever-arm 13 is formed with the longitudinal opening 22, which is of sufficient size to allow the arm 12 to pass easily therethrough. The lever-arms each have the two opposite transverse bends in them, and are hinged, respectively, upon opposite sides of the 65 plate, and when these arms are folded down they cross the center of the plate and extend to the opposite side of the plate from where they are hinged.

70 In Figs. 6 and 7 the arm 13 is omitted, and the device, which in Fig. 6 forms a clasp, is constructed with the single arm or post 12.

75 In order to securely hold the top plate, 14, and the hinge-plate 10 in their true relative positions, I form the hinge-plate, when cutting 80 the same out, with the perforations 22*, into which take the locking projections 23, which I construct upon the top plate by punching the material up when stamping out the plate. By virtue of such locking means, which are 85 clearly shown in Fig. 5, the two plates are prevented from moving on each other in operating the button, so that the slots of the two respective plates will always be maintained in the same relation.

90 Having thus described my invention, I claim as new and desire to secure by Letters Patent—

1. In a hinged-shoe button, the combination, as hereinbefore set forth, with the cap-plate and the bottom plate set therein, and the arms of the button provided with hinging ends, of 5 the hinge-plate suitably slotted to receive the hinging ends of the arms and formed with perforations, the top plate slotted to admit the arms and placed in contact with the hinge-plate, and provided with locking projections 10 for entering the perforations of the said hinge-plate and locking the same fixedly thereto, substantially as and for the purpose herein described.
2. In a hinged-shoe button, the combination, 15 with the hinge-plate 10, provided with the H-shaped slot and formed with perforations, of the top plate, 14, provided with the slot 15, and locking projections 23, constructed to permanently secure the plates against rotation and 20 secure the T-shaped ends of the levers, as described.
3. The combination, as hereinbefore set forth, with the cap-plate 8 and the bottom plate, 9, seated therein, the hinge-plate 10, provided with the slot 11 and formed with 25 the perforations 22*, and the top plate, 14, provided with the slot 15, and having the locking projections 23, for entering the said perforation 22 of the hinged plate, which is intermediate the said top and bottom plates, of the arms 30 provided with hinging ends which are hinged within the slot 11 of the hinge-plate, and which pass through the slot 15 of the top plate, 14, substantially as and for the purpose herein described.

JOHN COSTELLO.
